TABLE TOP CONSTRUCTION

John W. Beiger, Ludington, Mich., assignor to
The Carrom Company, Ludington, Mich.

Application January 16, 1933, Serial No. 651,872

5 Claims. (Cl. 45—31)

This invention relates to my invention set forth in my application for Letters Patent Serial No. 649,925, filed January 3, 1933, for Table top construction.

5 The objects of this invention are:

First, to produce a table top in which a flexible cover is stretched over an inserted top panel and held in place with the elimination of any gap between the panel and the surrounding frame 10 wherein dust or other dirt may collect.

Second, to provide such a table top construction in which the panel and frame are wedged together and held securely.

Third, to provide such a construction in which 15 very few parts are easily put together to obtain the desired result.

Further objects and advantages pertaining to economies of construction and operation will appear from the description to follow. A preferred construction of my device is illustrated in the accompanying drawing, in which:

Fig. 1 is a partial perspective view partly in section showing my table top construction assembled.

25 Fig. 2 is a partial perspective view partly in section showing the parts in disassembled relation.

Fig. 3 is a bottom plan view of my construction.

30 Fig. 4 is a bottom plan view of the top panel showing the flexible cover partly in place.

The parts will be identified by their numerals of reference which are the same in all the views.

35 1 is a table top panel that may be of wood, press wood, ply wood, sheet metal, or any other desired material. 2 is a frame, here shown as mitered at the corners. 3 is a flexible table top cover that may be of leatherette, fabric, or any 40 suitable material. The frame 2 is of a size to receive the top panel 1 and has an inwardly projecting, downwardly facing beveled portion 4 and a portion 5 against which a retaining strip may be secured to retain the top panel in 45 position, as will be described.

The table top panel 1 has a beveled edge 6 adapted to engage or mate with the beveled portion 4 of the frame so that the top of the panel 1 will be substantially flush with the top 50 of the frame 2. The flexible cover 3 is stretched over the top of the panel 1 and over the beveled edge 6 and around the edge of the panel where it is rolled or otherwise forced into the kerf 7 on the rear side of the panel. This kerf is spaced 55 from the edge of the panel and extends com-

pletely around the edge of the bottom portion of the panel. The cover 3 is cut away at the corner as at 8 to allow folding and rolling in the kerf 7, as is shown in Fig. 4. The rolling-in operation, or the insertion, is accomplished in 60 the usual way and glue may be inserted in the kerf to hold the flexible cover in place. The cover is placed in the frame and retaining or attaching strips 9 are placed in abutment with the bottom of the panel 1 to hold it tightly 65 against the beveled portion 4 of the frame. These perimetrically arranged strips not only hold the table top in position, but clamp the fabric to the bottom of the top panel, holding the fabric securely and assuring such holding even if 70 the fabric comes out of the kerf 7.

The retaining strips 9 are held in place by nails 10 extending therethrough and into the frame or by any suitable fastening means.

The nailing is a simple operation and is preferred. The panel 1 is securely wedged against the bevel 4 of the frame to make a tight joint in which no dust or dirt will collect. The wedge action tends to hold the table cover 3 in proper position and the snubbing of the table cover 80 around the edge of the panel 1 makes a very desirable fastening arrangement which is much more secure than could be obtained by similar means without the snubbing.

I have described my invention in the embodiment preferred by me, but wish to claim the same broadly as well as specifically as pointed out in the appended claims.

Having thus described my invention, what I claim as new and desire to secure by Letters 90 Patent is:

1. In a table top construction, a top panel having a beveled edge and a kerf on the side opposite the bevel and spaced from the edge, a flexible cover over the panel and bevel with its edges rolled in said kerf, a frame adapted to receive said top panel and having an inwardly-extending downwardly-facing bevel to engage said beveled edge, and having a portion thereon to receive a retaining strip, a retaining strip in 100 engagement with the bottom of said top panel, and nails holding said retaining strip to said frame, whereby the beveled edge of said top panel is held against said downwardly-facing bevel.

2. In a table top construction, a top panel having a beveled edge and a kerf on the side opposite the bevel and spaced from the edge, a flexible cover over the panel and bevel with its edges rolled in said kerf, a frame adapted to 110

receive said top panel and having an inwardly-extending downwardly-facing bevel to engage said beveled edge, a retaining strip in engagement with the bottom of said top panel, and 5 means for holding said retaining strip to said frame, whereby the beveled edge of said top panel is held against said downwardly-facing bevel.

3. In a table top construction, a top panel having a beveled edge, a flexible cover over the panel and bevel snubbed around the edge of and fastened to said panel by fastening means, a frame adapted to receive said top panel and having an inwardly-extending downwardly-facing bevel to engage said beveled edge, and having a portion thereon to receive retaining strips perimetrically arranged, retaining strips perimetrically arranged in engagement with the bottom of said top panel and the edge of the flexible cover, and nails holding said retaining strip to said frame, whereby the beveled edge of said top panel is held against said downwardly-facing bevel and the edge of the flexible cover is clamped against the bottom of the top panel.

25 4. In a table top construction, a top panel having a beveled edge, a flexible cover over the panel and bevel snubbed around the edge of and

fastened to said panel with fastening means, a frame adapted to receive said top panel and having an inwardly-extending downwardly-facing bevel to engage said beveled edge, retaining strips perimetrically arranged in engagement with the bottom of said top panel and the edge of said flexible cover, and means for holding said retaining strip to said frame, whereby the beveled edge of said top panel is held against said downwardly-facing bevel and the edge of said flexible cover is clamped against the bottom of the top panel.

5. In a table top construction, a top panel having a beveled edge, a flexible cover over the panel and bevel, a frame adapted to receive said top panel and having an inwardly-extending downwardly-facing bevel to engage said beveled edge, retaining strips perimetrically arranged in engagement with the bottom of said top panel, the edge of said flexible cover and the inner edge of said frame, and means for holding said retaining strip to said frame, whereby the beveled edge of said top panel is held against said downwardly-facing bevel and the edge of said flexible cover is clamped against the bottom of the top panel.
